UNITED STATES PATENT OFFICE.

WALTER H. COE, OF PROVIDENCE, RHODE ISLAND.

DEVICE FOR APPLYING METALLIC LEAF.

SPECIFICATION forming part of Letters Patent No. 668,849, dated February 26, 1901.

Application filed February 20, 1899. Serial No. 706,271. (No model.)

To all whom it may concern:

Be it known that I, WALTER H. COE, a citizen of the United States, residing at and whose post-office address is No. 165 Evanston street, 5 Providence, in the State of Rhode Island, have invented an Improvement in Devices for Applying Metallic Leaf from a Package-Roll, of which the following is a specification.

The object of my invention is to provide a 10 conveniently-operated device for applying metallic leaf from a package-roll to the surface which is to be decorated; and it consists in the improved construction and arrangement of parts, as hereinafter described and 15 claimed.

In the accompanying drawings, Figure 1 represents a side elevation of my improved device for applying metallic leaf for decorating purposes. Fig. 2 represents a rear edge 20 view when held in the position shown in Fig. 1. Fig. 3 represents a side view with the hinged side turned back at a right angle with the plane of the opposite side and shown in section to fully illustrate the adjusting-screw 25 for the tension-spring in side view without obstruction. Fig. 4 represents a side view of the pressure-brush and its holder separate from the case. Fig. 5 represents a central vertical section of the brush-holder. Fig. 6 30 represents a side view of the pressure-brush separate from the holder, and Fig. 7 represents a forward end view of the brush-holder.

In the drawings, A represents the case, in 35 which the spirally-wound package-roll B is held to rotate upon the bearing-stud C, the said package-roll being suitably frictioned to prevent the loose rotation of the package-roll in unwinding by means of the flat spring D, which is adapted to friction the side of the 40 package-roll, the said spring being attached at its end *a* to the hinged side E of the case and provided with a perforation *c*, (shown in dotted lines in Fig. 1,) adapted to pass over the end of the bearing-stud C when the side 45 E is closed, as shown in Fig. 2. The hinged side E is also provided with the adjusting-screw *v*, by means of which the pressure of the spring D against the side of the package-roll may be adjusted to suit the requirements 50 of the case. The hinged side E is also provided with a perforation *b*, adapted to receive

the end of the outer stud F, and to the outer side of the side E of the case is secured the hook *e*, which is pivoted at the point *f* and adapted to enter the notch or groove *g* at the 55 end of the stud F to lock the closed side E firmly in position, as shown in Figs. 1 and 2. A washer *h* is placed upon the stud C and secured to the side E of the case to prevent the side of the package-roll from bearing against 60 the flat inner surface of the side E'.

The pressure-brush G consists of the flexible brush *j*, provided at its upper portion with a ferrule *k*, by means of which the brush is adapted to fit the socket *l* of the brush-holder 65 H, the said brush-holder being provided with the transverse tube *m*, which loosely fits upon the stud F, and the side E' of the case is provided with a perforation *n*, adapted to receive the pin *o* of the brush-holder H to lock the 70 same in position and prevent the rotation of the brush-holder upon its supporting-stud F. The removable brush G is retained in its socket *l* by means of the set-screw *p*. At the lower side of the brush-holder is placed the 75 guide I, which serves to hold the supporting-strip and the metallic leaf in proper position for continued use when the brush has been raised from the surface *t*, which is to be decorated, the said guide serving to prevent the 80 supporting-strip from being thrown out of line with the pressure-brush, by means of which the metallic leaf *r* is transferred from the supporting-strip *s* to the surface *t*.

In the package-roll B the metallic leaf *r*, 85 which is indicated by the dotted line, is held at the inner side of the supporting-strips *s*, and when the package-roll B has been placed upon the bearing-stud C and the hinged side E closed upon the stud F and secured in its 90 closed position by means of the hook *e* the supporting-strip is to be threaded between the guide I and the under side of the brush G, the metallic leaf *r* being at the under side of the supporting-strip *s*, as shown in Fig. 3, 95 and by means of the guide I the metallic leaf will at all times be retained in position for ready application to the surface *t*.

I claim as my invention—

1. In a device for applying metallic leaf 100 from a package-roll, the combination of the holding-case provided with the hinged side,

the stud, and the locking means engaging with the stud, with the removable holder for the pressure-brush, held upon the stud, and the pressure-brush removable from its holder, substantially as described.

2. In a device for applying metallic leaf from a package-roll, the combination of the package-roll, and the pressure-brush, with the

guide for holding the supporting-strip in line with the under side of the brush, substantially as described.

WALTER H. COE.
